By Knight, Postatty & Co.

UNITED STATES PATENT OFFICE.

ANTON OHNEMUS, OF QUINCY, ILLINOIS, ASSIGNOR TO THE EXCELSIOR STOVE AND MANUFACTURING COMPANY, OF SAME PLACE.

NESTABLE STOVEPIPE.

SPECIFICATION forming part of Letters Patent No. 645,001, dated March 6, 1900.

Application filed October 7, 1899, Serial No. 732,855. (No model.)

To all whom it may concern:

Be it known that I, ANTON OHNEMUS, a citizen of the United States, residing at Quincy, in the county of Adams and State of Illinois, have invented certain new and useful Improvements in Nestable Stovepipes, of which the following is a full, clear, and exact description, reference being had to the accompanying drawings, forming part of this description.

10 My invention relates to that class of stovepipes so constructed that they may be shipped in collapsed condition nested together, so as to economize space, the object of the invention being to so construct pipe-sections of this description that they may be readily joined at the meeting edges by even an unskilled workman and the seams being so formed that when produced they will be firmly held against lateral or longitudinal displacement.

20 I am aware that it is not new to construct collapsible and nestable stovepipe-sections; but as heretofore made such sections have usually been provided with the usual overlapping longitudinal tongues that form the seams and 25 the seams being secured by a rivet inserted in the upper end of such section to prevent the seams from springing open when another section of pipe is forced over the end thereof.

Another method of forming the seams has 30 been to cut tongues from the pipe-sections that overlapped the tongues of the seam, so as to avoid its springing open. In the use of a rivet it is necessary that the person producing the seam to join the edges of the pipe-section be 35 a workman who is capable of applying the rivet and has the necessary facilities for so doing. The use of the tongues referred to is objectionable in that they are liable to become broken or fractured in the process of manu-

40 facture of the pipe-sections or broken off in handling or transportation of the pipe-sections. It has been my aim to produce a pipe-section of such construction that the objectionable features of such sections as heretofore made are entirely overcome and, further-

45 more, to produce an article in which the seam may be readily made by any person, whether a skilled workman or not, the form of the article being such that it is only necessary to use 50 a hammer or mallet in making the seam and

securing it firmly to avoid liability of displacement thereof.

Figure I is a perspective view of one end of a pipe-section constructed in accordance with my invention. Fig. II is an end view, shown 55 enlarged, of the meeting or tongue edges of the pipe-section. Fig. III is an elevation of the end of the section in open condition. Fig. IV is an elevation showing the seam thereof secured. Fig. V is a view showing a number 60 of pipe-sections in collapsed condition nested together for shipment.

1 designates a pipe-section provided with longitudinal tongues 2 and 3, designed to be interlocked with each other and to be flattened 65 to form a seam by the use of a hammer or mallet in the usual manner in which such seams are commonly made.

One of the edges of the pipe-section is cut away diagonally at 4 at the end of the section, the cut being produced through the outer tongue 2 as well as through the adjacent portion of the body of the section. When the seam is to be produced, the edges of the section are brought together so that the tongue 70 2 enters beneath the tongue 3, and the tongues are then flattened in the usual manner by the use of a hammer or mallet. The corner 3^a at the end of the tongue 3 at this time projects 75 beyond the diagonal cut-away portion 4 of the 80 opposite edge of the section to the extent indicated by the dotted line A, Fig. III. The corner 3^a of the tongue 3 is then bent backward on the line A, Fig. III, over the diagonal cut-away portion of the opposite edge of the 85 section, as seen in Fig. IV, and firmly hammered down, so as to secure the same in an effectual manner against springing open or 90 against endwise displacement. It will be seen that this manner of producing a seam is extremely inexpensive and is so simple that any person may readily secure the same to connect the edges of the pipe-section, as the only implement necessary is a hammer or mallet by which the tongues are flattened and the 95 corner 3^a is bent over and lapped onto the same. Moreover, there is no part of the pipe-section that is liable to become broken or injured in any way in the process of manufacture or in handling during transportation. 100

While I have referred to the herein - described pipe as a "stovepipe," I do not wish to be restricted to a pipe of this nature, as the construction might be of utility in other descriptions of pipes.

I claim as my invention—

A pipe-section having interlocking edges to form a seam, said section having one of the

edges cut away at the end thereof to receive the coincident corner of the opposing tongue so when lapped thereover, substantially as described.

ANTON OHNEMUS.

In presence of—

JOHN J. FISHER,

GEORGE E. PHIRMON.
